(57) CLAIM

The ornamental design for a digital frame and organizer, as shown and described.

DESCRIPTION

FIG. 1 is a perspective view of the digital frame and organizer showing my design with the top and front compartments in the open positions;

FIG. 2 is a perspective view thereof with the top and front compartments in the closed positions;

FIG. 3 is a rear elevational view thereof with the top compartment in the open position;

FIG. 4 is a front elevational view thereof with the top compartment in the open position;

FIG. 5 is a top plan view thereof with the top compartment in the open position;

FIG. 6 is a bottom plan view thereof;

FIG. 7 is a left side view thereof with the top and front compartments in the open positions; and,

FIG. 8 is a right side view thereof with the top and front compartments in the open positions.

The broken lines showing the images in FIG. 1 are for illustrative purposes only and form no part of the claimed design.
